UNITED STATES PATENT OFFICE.

HENRY JESS AND CARL CHRISTENSEN, OF SABULA, IOWA.

DESIGN FOR A FEEDING-TROUGH.

... ILLUSTRATION forming part of Design No. 32,018, dated December 19, 1899.

Application filed November 10, 1899. Serial No. 736,563. Term of patent 14 years.

To all whom it may concern:

Be it known that we, HENRY JESS and CARL CHRISTENSEN, citizens of the United States, residing at Sabula, in the county of Jackson, 5 and State of Iowa, have invented and produced a new and original Design for Feeding-Troughs; and we do hereby declare the following to be a full, clear, and exact description of the same.

Our invention relates to designs in feeding-troughs; and the novel features consist, essentially, in a trough, having sustaining-stays at each end, with partitions across the trough dividing the trough into feeding-stalls; also 15 in a longitudinal partition over the trough, dividing the cross-partitions and presenting individual feeding-stalls on both sides of the trough farther in and a filling-sprout projecting up from the trough between the cross-partitions.

A full description of our design will be set out in the following specification and illustrated in the accompanying drawing.

The figure shows a perspective of our design.

Referring to the drawing, A designates the trough. At each end of the trough is a sustaining-stay B, to which the trough is secured and by which it is sustained. In the notches

in the upper edge of the trough are set cross-partitions D, which divide the trough into stalls E. A longitudinal partition G is secured in notches in the sustaining-stays and in the cross-partitions D, dividing the cross-partitions and engaging the stays B, thereby forming individual feeding-stalls on both sides of the trough. Between two of the cross-partitions D, extending up from the trough, is a sprout H.

It will be seen that the essential features 40 presented in this design are the individual feeding-stalls on both sides of the trough formed by the cross and longitudinal partitions; also a sprout projecting up from the trough, and the whole device sustained on 45 spreading stays.

Having now described our design, what we claim is—

The design for a feeding-trough, as herein described and shown.

In testimony whereof we affix our signatures in the presence of two witnesses.

HENRY JESS.
CARL CHRISTENSEN.
